THEODORE SCHEFFLER, OF PATERSON, NEW JERSEY.

Design No. 3,929, dated March 22, 1870.

DESIGN FOR MACHINERY FOR MAKING ICE.

The Schedule referred to in these Letters Patent and making part of the same.

To all whom it may concern:

Be it known that I, THEODORE SCHEFFLER, of Paterson, in the county of Passaic, in the State of New Jersey, have invented and produced a new and original Design for "Machinery for Making Ice," of which the following is a specification.

Figure I is a front elevation; and

Figure II, a side view of the machinery, with the water-tank shown in section in both figures.

My design consists in the arrangement of the condenser A upon the bottom plate B of the water-tank C, and attaching on two sides of said condenser A the air-pumps D, the connecting-pipes between these air-pumps D and the condenser A forming a coil, E, surrounding the air-pumps and condenser, and the whole of them being inclosed in the water-tank C.

Upon the top of the condenser A a frame, F, is ar-

ranged, having near its top on opposite sides, and directly above the air-pump D, steam-cylinders G attached. The pistons in said steam-cylinders being connected with the pistons in the air-pumps through the rods J and J.

On the top ends of the cylinders bearings H are placed, to support the shaft K, provided with cranks L on each end, connected through rods M with pins fastened to the piston-rods J to regulate the motion.

I claim as my invention—

The design and arrangement of the different parts of machinery for making ice, as described and shown.

THEODORE SCHEFFLER.
